DESIGN FOR A CARPET-PATTERN.

Specification forming part of Design No. 5,126, dated July 11, 1871.

To all whom it may concern:

Be it known that I, GEORGE CURTIS WRIGHT, of the city of New York, county of New York and State of New York, have invented and produced a new and original Design for a Pattern to be wrought into Tapestry, Brussels, or other Carpeting in such colors as may be desired; and I do hereby declare that the photographic print accompanying this specification does give and convey, to any one skilled in the art of carpet-weaving, a more definite and thorough description of the nature of my invention than it is in the power of language otherwise to convey, and

it is sufficient to enable any one skilled in the art of carpet-weaving to use my invention.

What I claim as my invention, and desire to secure by Letters Patent, is—

The configuration of the design hereunto annexed, when made by being inwrought into tapestry, Brussels, or other carpeting in the form similar to the photographic print accompanying this specification.
